DESIGN FOR A FILTER DISK FOR DRIP COFFEE MAKERS

Amos Peterson, Berwyn, Ill., assignor to Club
Aluminum Products Co., Chicago, Ill., a corpora-
tion of Delaware

Application August 31, 1942, Serial No. 108,082

Term of patent 14 years

To all whom it may concern:

Be it known that I, Amos Peterson, a citizen
of the United States and a resident of Berwyn,
county of Cook, and State of Illinois, have in-
vented a new, original, and ornamental Design
for a Filter Disk for Drip Coffee Makers, of
which the following is a specification, reference
being had to the accompanying drawing, form-
ing a part thereof, in which Fig. 1 is a perspec-

tive view of a filter disk for drip coffee makers,
showing my new design. Fig. 2 is a top view
of the same; and Fig. 3 is a vertical detail sec-
tional view through a part of the filter disk as
taken on the line 3—3 of Fig. 2.

I claim:

The ornamental design for a filter disk for
drip coffee makers, substantially as shown.
AMOS PETERSON.
